CLAIM

The ornamental design for an axial piston machine, as shown and described.

DESCRIPTION

FIG. 1 illustrates a perspective view of the axial piston machine, showing my new and ornamental design;

FIG. 2 illustrates a side view thereof;

FIG. 3 illustrates a side view thereof;

FIG. 4 illustrates a side view thereof, opposite to FIG. 2;

FIG. 5 illustrates a side view thereof, opposite to FIG. 3;

FIG. 6 illustrates a top plan view thereof; and,

FIG. 7 illustrates a bottom plan view thereof.
